FISHING REEL CASE

James L. Hvale, Chicago, and John A. Eckmann, Morton Grove, Ill., assignors to Flambeau Plastics Corporation, Baraboo, Wis., a corporation of Wisconsin

Filed Jan. 13, 1964, Ser. No. 78,168

Term of patent 14 years

(Cl. D31—4)

The side not shown is identical to that shown in FIGURE 2.

We claim:

The ornamental design for a fishing reel case, substantially as shown and described.
